UNITED STATES PATENT OFFICE.

AUGUST RAST, MICHAEL GASSER, AND HEINRICH ZWANZIGER, OF VIENNA, AUSTRIA-HUNGARY.

PRESS FOR STAMPING METAL SEALS, &c.

SPECIFICATION forming part of Letters Patent No. 373,905, dated November 29, 1887.

Application filed December 8, 1886. Serial No. 221,030. (No model) Patented in Germany July 21, 1886, No. 38,981; in Belgium July 22, 1886, No. 73,931; in England July 23, 1886, No. 9,557; in France July 23, 1886, No. 177,558, and in Austria-Hungary December 19, 1886, No. 28,230 and No. 62,297.

To all whom it may concern:

Be it known that we, AUGUST RAST, MICHAEL GASSER, and HEINRICH ZWANZIGER, all subjects of the Emperor of Austria-Hungary, residing at Vienna, Austria-Hungary, have invented a new and useful Press for Stamping Metal Seals, &c., (for which we have obtained patents in Austria-Hungary, No. 28,230 and No. 62,297, of December 19, 1886; in Germany, No. 38,981, of July 21, 1886; in England, No. 9,557, of July 23, 1886; in France, No. 177,558, of July 23, 1886, and in Belgium, No. 73,931, of July 22, 1886,) of which the following is a specification.

15 Our invention relates to a press for stamping metal seals, &c., which has the characteristic peculiarity that the movable die is guided in a straight line and that no springs are used, neither for ejecting the pressed seal nor for 20 stopping or actuating any part of the press.

In the annexed drawings, Figure 1 represents a side view of the press; Fig. 2, a view from above. Fig. 3 represents a longitudinal section of the press when opened; Fig. 4, when closed. Fig. 5 is a front view, (closed position,) and Fig. 6 the same in an open position. Figs. 7, 8, and 9 represent the sliding piece in different views. Figs. 10 and 11 represent the lower movable die. Fig. 12 represents 30 the upper stationary die.

Similar letters of reference indicate corresponding parts.

The one lever-handle of the press has on one end a casing, *a*, to which the second lever-handle, *b*, is movably connected by means of a bolt or trunnion, *f*. On both sides of the casing are arranged links *c*, which are movably connected on the one side by means of the bolt *d* to the sliding piece *g* (carrying the movable die *h*) and arranged in the casing *a*) and on the other side by means of the bolt *e* to the lever *b*. The sliding piece *g*, sliding with lugs or studs *o* in slots of the casing, (which lugs prevent it from turning,) is centrally perforated and carries the one movable die *h*, opposite to which the stationary die *i* is arranged in the casing.

45 The operation is the following: Having put the object to be pressed (seal metal, &c.) into the opening of the casing (marked by the let-

ter *q*) between both the dies *h* and *i*, (whereby 50 the centering of the seal, &c., is effected by the rest-support *m*, which may be applied either on the sliding piece *g*, as shown in the drawings, or on the stationary die *i*,) first, the sliding piece *g* is moved from the position 55 shown in Fig. 3 into that of Fig. 4, by means of the lever-handle *b* and links *c*, so that the upper cylindrical part of the sliding piece embraces the object to be pressed, (seal metal, &c.) By the resistance of the seal the die *h* 60 is not moved at once. Only when the sliding piece *g* has moved so far that its inner shoulder pushes against the enlarged part of the die *h* the latter is carried along during the continued motion and pressed into the seal, 65 &c. By the arrangement of the links *c* laterally from the casing *a*, and in the longitudinal direction of the latter, the great advantage is attained that the links act almost in the direction of motion of the sliding piece *g*. On 70 the other hand, as the connecting-line of the centers of *e* and *f* is nearly horizontal, the point *d* (being rigidly connected with *e*) moves on its rotation about *f* faster on the beginning than afterward. The more the point 75 *e* approaches the position shown in Fig. 5 the more the upward motion is retarded, and, as mechanical work is the product of space and force, it is easily understood that if the product is to be the same the increase of the 80 one factor requires the decrease of the other. This is absolutely necessary, as the object to be pressed presents an increasing resistance. After pressing—that is to say, on the retro-grade movement of the lever *b*—the sliding 85 piece, together with the die *h* and the pressed object, is moved downward. Only when the key or bolt *k* (which is secured on both the ends in the casing *a* and extends through the slots *n* of the sliding piece *g* and die *h*) pushes 90 against the upper end of the slot of the die *h* the continued movement of the latter is stopped. The sliding piece *g*, the slot *n* of which is longer than that of the die *h*, continues to fall, so that the die *h* appears to ascend 95 and pushes out the finished seal. A screw or pin, *l*, of the sliding piece *g*, guided in a slot, *p*, of the die *h*, limits the motion of the latter

in regard to the sliding piece *g*, so that the former can never project over the upper edge of the latter. The two small openings *g'* on the upper edge of the sliding piece are designated for the passage of both the threads or cords.

Having fully described our invention, what we desire to claim and secure by Letters Patent is—

- 10 1. In a press for stamping metal seals, &c., the combination of two handle-levers with a casing, *a*, sliding piece *g*, movable die *h*, provided with slots *n* and *p*, stationary die *i*, bolts *d*, *e*, and *f*, and links *c*, key *k*, and screw *l*, all substantially as set forth, and for the purpose specified.

2. In a press for stamping metal seals, &c., the combination of the sliding piece *g*, movable die *h*, provided, respectively, with slots *n* and *p*, key *k*, and screw *l*, substantially as 20 described, for the purpose specified.

In testimony whereof we have signed our names to this specification in the presence of two subscribing witnesses.

AUGUST RAST.
MICHAEL GASSER.
HEINRICH ZWANZIGER.
